(57) **CLAIM**

The ornamental design for a VESA mount adapter bracket, as shown and described.

DESCRIPTION

FIG. 1 is a perspective view of a VESA mount adapter bracket showing my new design;

FIG. 2 is a front view thereof;

FIG. 3 is a back view thereof;

FIG. 4 is a right side view thereof, the left side view being a mirror image of FIG. 4;

FIG. 5 is a top view thereof; and,

FIG. 6 is a bottom view thereof.

The broken lines represent portions of the article and form no part of the claimed design.

1 Claim, 5 Drawing Sheets
